UNITED STATES PATENT OFFICE.

GEORGE EDWARD PRENTICE, OF BERLIN, CONNECTICUT.

BELT BUCKLE.

Application filed July 5, 1924. Serial No. 724,402.

To all whom it may concern:

Be it known that I, GEORGE E. PRENTICE, a citizen of the United States, residing at Berlin, in the county of Hartford and State 5 of Connecticut, have invented certain new and useful Improvements in Belt Buckles, of which the following is a specification.

My invention relates to improvements in belt buckles and the object of my improvement is to produce a belt buckle that is particularly adapted for use with belts that are made of rubber and involving to this end, the use of a plurality of individual contacts with the material of the free end of the belt, 15 each making a substantially positive gripping or holding effect though appreciably less than necessary in cases where a single gripping contact is employed.

In the accompanying drawing:—

20 Figure 1 is a front elevation of my improved belt buckle with parts of the belt.

Figure 2 is a rear elevation of the same.

Figure 3 is an edge view of the same.

25 Figure 4 is a sectional view on the line 4—4 of Fig. 2.

Figure 5 is a similar view to Fig. 4 with the parts in a different position.

Figure 6 is a plan view of the blank for the clamping lever.

30 Figure 7 is a sectional view on an enlarged scale on the line 7—7 of Fig. 4, showing the middle contacting part in the engaged position.

Figure 8 is a sectional view on the line 35 8—8 of Fig. 4, showing the side contact members.

My improved belt buckle comprises a front wall 10; rearwardly directed side walls 11 of flange-like form that are connected to the 40 top and bottom edges of said front wall 10; extensions of said side walls 11 that serve as supporting ears for the clamping lever 13 and are perforated to receive the pintles 14 thereof; and may have wings 15 on the two 45 sides that extend inwardly from the edges of said side walls 11. Said wings 15 are spaced from the front wall 10 and cooperate with the same and with the side walls 11 to provide a guide-way at the entrance portion or 50 mouth for the free end 16 of the belt.

As shown in Fig. 2 said entrance portion or mouth 17 is at the left end and the long arm 18 of the clamping lever 13 in the clamping position is swung towards the right of 55 the pintles 14.

Said long arm 18 is provided with means

of proper form for securing the fixed end 19 of the belt, said means in the present instance being in the form of a diminutive clamping lever 20.

The structure so far described is ordinary.

It is also ordinary to provide a crowning or rounded effect substantially as shown for the front wall 10, involving a forward bulging of the material. This condition, however, in the present instance I utilize in a special manner for effecting one of the results of the invention, as will be described.

Considering the portion or zone 21 of the front wall 10 that is adjacent and cooperates with the short arm 22 of the clamping lever 13, by reason of the crowning described, the different parts of said zone 21 are located at different distances or spacings from the axis of movement as determined by the 70 pintles 14. That is to say, the two side portions 23 are nearer the axis than the middle portion 24. Thus by suitable shaping and forming of the active portion or portions of the short arm 22 different contacting and 80 clamping effects may be obtained.

In order to obtain such effects in a simple manner the following details of construction are followed:—

The free edge 25 of the clamping lever 13 85 is used for cooperating with the two side portions 23 of the zone 21 by providing a simple straight edge for the same. Thus the pressure at the sides will be greater than at the middle. The parts are constructed and 90 arranged so that with the belt material for which the buckle is adapted the clamping pressure will be confined to the two sides 23 and whatever contact there may be at the middle 24 will not be effective for clamping 95 purposes.

Thus two individual contacting or clamping effects are obtained.

I provide a third clamping effect at the middle 24 by means of a separate clamping 100 lip 26 that is formed integral with the short arm 22, the material being sheared along the U-shaped line 27 and struck-up or bent along the folding line 28, the free edge 29 of said lip 26 serving as the clamping edge, and 105 which free edge 29 is of rounded form, as shown. Also, said middle clamping lip 26 is in spaced relation to the free edge 25 described.

As described, the clamping provided for in 110 my improved belt buckle involves what may be briefly described as a three-point contact

effect, with the different contacts distributed over the face of the belt.

I claim as my invention:

A belt buckle having a frame of channel form, comprising a front wall, a clamping lever supported from said frame and having a short arm for cooperating with said front wall for clamping a belt end, and said short arm having a set of active individual 10 contacting edges for engaging said belt, said set comprising a pair of side edges that are laterally spaced and a middle edge spaced longitudinally from said side edges, said

pair of side edges being the end parts of a single straight edge structure that extends 15 continuously and unbroken across substantially the entire width of the free end of said short arm, and said front wall being crowned or rounded for the zone that is opposed to said short arm and having the middle portion spaced from said free end to an extent to prevent clamping a belt against said middle portion by said straight edge structure.

GEORGE EDWARD PRENTICE.
